RAILWAY SIGNALING SYSTEM

Filed March 31, 1927

FIG. 1

UNITED STATES PATENT OFFICE

PAUL E. CARTER, OF BRONXVILLE, NEW YORK, ASSIGNOR TO GENERAL RAILWAY SIGNAL COMPANY, OF ROCHESTER, NEW YORK

RAILWAY SIGNALING SYSTEM

Application filed March 31, 1927. Serial No. 179,916.

This invention relates to railway train control systems in general, and has more particular reference to such systems for single track roads of the type known as absolute-permissive-block systems.

In one type of system for single track railroads certain signals are governed in one manner by trains moving in one direction and in a different manner by trains moving 10 in the opposite direction, and the means for changing from one manner of governing to the other comprises a stick relay energized by trains traveling in one direction and not energized by trains traveling in the other direction, the energization of the stick relays removing a usual tumble-down operation of signals and permitting operation of such signals in the manner usual in double track signal systems. In this manner a train going in 15 20 a given direction prevents all train movement in the opposite direction while permitting following trains to proceed under usual restrictions.

In systems of the character referred to above, it sometimes happens that a section of track becomes shorted out, due to a non-insulated hand car, or a crow bar, or the like bridging across the track rails, so as to thus de-energize a track relay. In such circumstances, the signals controlling traffic in both directions will be put to stop, and will remain in such stop position, even after the shorting influence has been removed, thus making the system inoperative and necessitating manual adjustment of certain parts of the system before the signals return to their normally clear position. In other words, a condition is brought about which is generally characterized as a lock-up, and which 30 35 40 amounts to signals being placed in a certain position due to a given track influence, and failing to return to their normal position upon said influence being removed.

With the above and other considerations in mind, it is proposed, in accordance with this invention, to provide means for preventing such a lock-up as referred to above. More specifically, it is proposed to employ stick relays for performing the usual function, 45 50 when energized, of removing the tumble-

down operation of certain signals, as is well known to those skilled in this particular art, such stick relays being cross-connected to each have its pick-up circuit running through a back contact of a neighboring stick relay, thereby to prevent simultaneous pick-up of such cross-connected relays and in this manner prevent a lock-up of the system. 55

Further objects, purposes, and characteristic features of the invention will appear as the description progresses, reference being had to the accompanying drawings, showing, solely by way of illustration, and in an entirely schematic manner, one form of the invention. In the drawings:—

Fig. 1 is a schematic view of an intermediate portion of a stretch of single track railway equipped with the present invention; and,

Fig. 2 is a schematic fragmentary view of a system susceptible of being locked up under certain conditions.

Referring to Fig. 1 of the drawings, there is shown an intermediate portion of a stretch of single track railway running between two passing sidings, constituted by track rails 1, divided into blocks B, C, D, and in the usual manner, by insulating joints 2, each block being provided with a usual track battery 2' and track relay T. Various corresponding parts in the different blocks are designated by similar reference characters with distinguishing subnumbers etc.

Wayside signals 3, 5, etc., are provided along the trackway for governing traffic in an easterly direction while signals 4 etc. are provided for governing traffic in a westerly direction, the signals being shown as color light signals giving the usual aspects for clear, caution, and danger, although these signals could equally well be of the position light or semaphore type.

Associated with each signal is a relay H arranged to govern the energization of the signal in a well-known manner, (the control devices and circuits therefor not being shown) the relay being of the polarized type having contact fingers assuming a biased neutral position when de-energized, and a position to the right or the left of the neutral,

depending on the polarity of energizing current, when the relay is energized.

Associated with each relay H is a relay Z, which is energized through a circuit including a contact finger of the relay H, whereby the Z relay is energized or de-energized according as the H relay is energized or de-energized.

Also associated with each H and Z relay is a stick relay S, having a stick circuit including a contact finger of the H relay which closes this stick circuit when in de-energized position; and a pick-up circuit including a contact finger and back contact of an adjacent stick relay associated with a signal for governing traffic in the opposite direction, whereby the two stick relays referred to, can not both pick up at the same time.

For the purpose of explaining the present invention, it will be necessary to only very briefly discuss the usual operation of an absolute-permissive-block system of the character shown in Fig. 1, and hence the following description of such operation will not be complete in all its details, and for further explanation of its operation, reference should be had to Patents 1,294,736 of February 18, 1919 to S. N. Wight, and 1,386,073 of August 2, 1921 to Neil D. Preston, and more particularly to the latter.

To simplify the wiring diagram and the explanation, positive, negative, and common, wires from a suitable source of energy, as for example a storage battery, have been indicated by the symbols, PB, NB, and C, respectively.

Assuming, for the purpose of illustration, that a train is traveling in an easterly direction, that is, from left to right, as viewed in the drawing, on the stretch of track shown, when it enters block B, relay T³ will be de-energized to drop its contact fingers 7 and 8, dropping of the contact finger 7 operating to de-energize relay 4H governing signal 4, through a circuit which is obvious from the drawing. On de-energization of relay 4H, relay 4Z is de-energized through an obvious circuit, to thus put energy on the signal 4 through contact finger 9 and back contact of relay 4Z, to put signal 4 to stop. De-energization of relay 4Z takes energy off of the wire 11, at contact finger 10, leading to control means for the next signal to the right which governs west bound traffic to thereby put such signal to stop, and this well known tumble down effect carries through to the easterly entrance end of the single track stretch, to thereby prevent any west bound traffic from entering on the single track portion between the two sidings until east bound traffic has left this stretch of track.

Upon the train in question passing into block C, relay T⁴ is de-energized to drop its contact fingers 11', 12 and 13. Dropping away of contact finger 12 de-energizes relay

3H to thereby set signal 3 at stop and protect the train in question from following trains.

Upon de-energization of relay 3H, relay 3Z is de-energized at the polar contact finger 14 of relay 3H, but inasmuch as the relays 3Z, 4Z, etc. are made slow acting, in any desired manner, the contact finger 15 of relay 3Z does not drop away until after relay 3S has picked up its contact finger 16 through a pick-up circuit which can be readily traced from the drawing and which includes contact finger 15 and front contact of relay 3Z, contact finger 18 and back contact of track relay T⁴, contact finger 17 and back contact of relay 4Z, and contact finger 18 and back contact of relay 4S. Upon picking up the contact finger 16 of stick relay 3S, a stick circuit is completed to maintain relay 3S in energized condition, such stick-up circuit including contact finger 16 and front contact of relay 3S, and contact finger 19 and neutral contact of relay 3H.

The function of stick relay 3S, is to make inoperative the normal tumble-down connection between the various relays 5H, 3H etc., and a consideration of Fig. 1 shows that on energization of stick relay 3S, its contact finger 20 is picked up to thereby put reverse energy on a relay 1H (not shown in the drawing) which controls the next signal to the left of signal 3, for controlling traffic in an easterly direction, such relay 1H being energized through a circuit which includes the contact finger 20 and front contact of relay 3S, wire 21, contact finger 22 and back contact of relay 3Z, wire 23, contact finger 8 and front contact of relay T¹, etc. Were it not for the stick relay 3S being picked up, dropping away of contact finger 22 of relay 3Z would take all energy off of relay 1H, in a typical tumble-down circuit fashion. The arrangement as shown in the drawing is such that the stick relays are energized to prevent the tumble-down feature from operating with regard to those signals in the rear of a moving train and governing traffic in the direction under consideration while those signals governing traffic in the opposite direction do not have their stick relays so energized, so that the tumble-down feature is operative, as explained above, with regard to the operation, for example, of signal 6 (not shown) through wire 11, upon the setting of signal 4 to danger.

As the train progresses along the track-way, and enters block D, track relay T⁴ is de-energized and operates through its contact finger 24 to maintain the above referred to signal 6 (not shown), at stop and through its contact finger 25, to maintain de-energized the relay 3H, to thereby keep signal 3 at stop.

Upon the train entering block E relay T⁴ is picked up, while relay T⁵ is de-energized to drop its contact fingers 26 and 27.

In the same manner as for the relays as

sociated with signal 3, the relay 5H is de-energized thus putting its signal 5 at stop and causing de-energization of relay 5Z after a short period of time, during which period 5 of time the stick relay 5S is picked up through a pick-up circuit including contact finger 28 and front contact of relay 5Z, contact finger 27 and front contact of relay T⁵ etc., and is then maintained picked-up by a 10 stick circuit including its own contact finger 29 and front contact, and contact finger 30 of relay 5H in de-energized position. With contact finger 31 picked up, negative energy is put on relay 3H, controlling signal 3, 15 through a circuit including contact finger 31 and front contact of relay 5S, contact finger 32 and back contact of relay 5Z, contact finger 25 and front contact of relay T⁴ etc., to thus put signal 3 at caution as it should be. 20 Also, with relay 3H now reenergized, even though reversely, relay 3Z is energized and contact finger 22 reapplies positive energy to relay 1H (not shown) permitting the signal 1 (not shown) to clear.

25 It is seen from the above that the stick relays, such for example, as 5S are arranged to be energized for traffic in but one direction, and when so energized, prevent the tumble-down operation between signal relays, such, for instance, as relays 5H and 3H, and instead permit these relays to be governed in the usual manner in double track signal systems, namely, to permit the signals to assume stop, caution and clear indications 30 in accordance with the traffic conditions 35 in accordance with the traffic conditions ahead, so as to permit following trains to proceed under the usual restrictions.

Referring to Fig. 2, there is shown a usual form of connection for the stick relays 3S 40 and 4S, wherein contact fingers 13' and 13'' are employed to respectively control the pick-up circuits for the relays 3S and 4S, instead of using a single contact finger such as 13 of Fig. 1. Assume, for the moment, that the 45 system shown in Fig. 1 is modified to the extent of the change indicated in Fig. 2, that is, that the pick-up circuit for relay 3S includes wire 32¹ of Fig. 1, and a contact finger 13', to a source of energy C, as in Fig. 2, and 50 that the pick-up circuit for relay 4S includes wire 33 of Fig. 1, and a contact finger 13'' to a second source C as in Fig. 2. If now, track relay T⁴ is shunted out, in the section C, other than by a train traveling over the rails, such 55 for example as by a hand car which is not properly insulated, or by a crow bar or the like, bridging across the two rails, the relay T⁴ will drop and through its finger 11' and 12 will respectively de-energize signal 60 control relays 4H and 3H which in turn will place signals 4 and 3 respectively to danger. Before dropping away of the contact fingers of the relays 4Z and 3Z which, are, of course, de-energized on de-energization of their 65 corresponding H relays, the two stick relays 4S

and 3S will respectively be energized through their pick-up circuits, which, in the modification of Fig. 2, assumed for the moment, include respectively contact finger 13'' and back contact of relay T⁴ and contact finger 13' and back contact of relay T⁴. When once energized through their pick-up circuits, the stick relays 4S and 3S will remain stuck up through their stick circuits which have been traced above.

The next signal to the left of signal 3, governing traffic in an easterly direction will go to caution, while the next signal to the right of signal 4, governing west bound traffic, will likewise go to caution, upon the signals 3 and 4 going to danger.

Upon removal of the short circuit between the track rails 1 in the block C, relay T⁴ will be picked up, but the various signals at stop and caution will remain at stop and caution even though the condition which resulted in their assuming their stop and caution positions, has been removed.

This is due to the fact that relay 3H, controlling signal 3, can not be energized unless stick relay 4S is de-energized, and relay 4H, controlling signal 4, can not be energized unless stick relay 3S be de-energized, since the energizing circuits for relays 3H and 4H include, respectively, contact fingers and back contacts 34 and 35, respectively, of stick relays 4S and 3S. In other words, in order that the signals set at danger be restored to clear, their control relays must be energized, and in order that such control relays be energized, it is necessary that stick relays be de-energized, and since the stick relays in question are energized and can not be de-energized except by breaking their stick circuits by energization of the control relays H for the signals, a locked-up condition exists which cannot be overcome except by manually breaking the stick circuit circuit for one of the stick relays 3S or 4S.

It should be particularly noted that the stick circuit for each of the stick relays 3S and 4S includes a contact finger of the corresponding H relay in de-energized position and the energizing circuit for each of the relays 3H and 4H includes, respectively, a back point of the other S relay, that is, of relays 4S and 3S respectively. Thus, energization of the H relays depends on de-energization of the S relays, and, in turn, de-energization of the S relays depends on energization of the H relays, thus giving a locked-up condition incapable of automatic restoration.

In order to overcome any possibility of the occurrence of a condition such as just described above, the construction shown in Fig. 1 is employed, wherein, as described above, the stick relay 3S for example has a pick-up circuit passing through the contact finger and back contact of stick relay 4S. In like manner stick relay 4S has a pick-up circuit which

includes a contact finger 35 and back contact of stick relay 3S. In this manner the two stick relays 3S and 4S are so connected that they cannot pick up simultaneously, to thus avoid any possibility of a lock-up such as above described.

Consider, for example, the shorting of the track rails 1, by a crowbar or the like, in the block C, to thus cause de-energization of track relay T⁴, as was assumed above when a locked-up condition resulted with a usual construction, as shown in Fig. 2. Under the same conditions, with the construction of Fig. 1, the relays 3H and 4H, as in the former case, will be de-energized, and will set their respective signals 3 and 4 at stop, and after an interval of time, will cause the dropping away of the contact fingers of the slow acting relays 3Z and 4Z.

It will be noted that the pick-up circuit for relay 3S requires 2Z up and 4Z down, whereas the pick-up circuit for relays 4S requires 3Z down and 4Z up, or, in other words the requirements for pick-up of the two stick relays are diametrically opposed and hence cannot simultaneously exist. Accordingly, depending upon which one of the two Z relays, 3Z or 4Z, drops its contact finger 15 or 17 first, is dependent which one of the two stick relays, 3S and 4S, picks up. If one stick relay is once picked up, the other stick relay cannot pick up, since each one has its pick-up circuit running through a back contact of the other one.

Assuming, for example, that relay 3Z drops its contact finger 15, before relay 4Z drops its contact finger 17, the pick-up circuit for the relay 4S will be completed, and the 4S relay will pick-up and thus prevent relay 3S from picking up, due to pick-up of contact finger 18 of relay 4S.

The condition that now exists is that signals 3 and 4 are at stop, the relays 3H and 4H are de-energized, relay 4S being picked up and stuck up, the relay 3S being de-energized, and relays 3Z and 4Z both being de-energized. In such circumstances, upon removal of the means causing de-energization of track relay T⁴, such track relay will pick up its fingers 11¹, 12 and 13. Picking up of finger 11¹ permits re-energization of relay 4H, since contact finger 35¹ of stick relay 3S is in its detracted position. Energization of relay 4H breaks the stick circuit for stick relay 4S at contact finger 36 of relay 4H, thus permitting contact finger 34 of stick relay 4S to assume its detracted position to thereby re-energize relay 3H.

Thus the various relays are restored to their normal positions, as likewise are the signals, upon removal of the condition which placed the signals at danger, so that the system automatically restores itself to normal operative condition.

From the connections and arrangements of

parts as shown in Fig. 1, it is seen that a locked-up condition due to causes such as enumerated above, is quite impossible, whereas with the arrangement as depicted in Fig. 2, and which has heretofore been generally employed, such a locked-up condition necessarily occurs upon every occurrence of a causation such as enumerated above.

The above rather specific description of one form of the invention, is shown solely by way of example, and is not intended, in any manner whatsoever, in a limiting sense. Obviously, the invention can assume many different physical forms, and is susceptible of numerous modifications, and it is intended to include, in this application, all such forms and modifications as come within the appended claims.

Having described my invention, I now claim:

1. In a traffic control system for single track, signal control means for governing traffic in one direction, signal control means for governing traffic in the opposite direction, an energizing circuit for each of the signal control means, a traffic responsive means controlling both of said energizing circuits, a first relay associated with, and controlled by, each of the signal control means, a second relay associated with each of the signal control means and controlling the energizing circuit of the other signal control means, each of said second relays having an energizing circuit controlled by said traffic responsive means.

2. In a traffic control system for single track, signal control means for governing traffic in one direction, signal control means for governing traffic in the opposite direction, an energizing circuit for each of the signal control means, a traffic responsive means controlling both of said energizing circuits, a first relay associated with, and controlled by each of the signal control means, a second relay associated with each of the signal control means and controlling the energizing circuit of the other signal control means, each of said second relays having an energizing circuit controlled by said traffic responsive means and by both of the said first relays.

3. In a traffic control system for single track, signal control means for governing traffic in one direction, signal control means for governing traffic in the opposite direction, an energizing circuit for each of the signal control means, a traffic responsive means controlling both of said energizing circuits, a first relay associated with, and controlled by, each of the signal control means, a second relay associated with each of the signal control means and controlling the energizing circuit of the other signal control means, each of said second relays having an energizing circuit controlled by said traffic responsive

means and by the said first relay controlled by the other signal control means.

4. In a traffic control system for single track, signal control means for governing traffic in one direction, signal control means for governing traffic in the opposite direction, an energizing circuit for each of the signal control means, a traffic responsive means controlling both of said energizing circuits, a first relay associated with, and controlled by, each of the signal control means, a stick relay associated with each of the signal control means and controlling the energizing circuit of the other signal control means, each of said stick relays having a pick-up circuit controlled by said traffic responsive means.

5. In a traffic control system for single track, signal control means for governing traffic in one direction, signal control means for governing traffic in the opposite direction, an energizing circuit for each of the signal control means, a traffic responsive means controlling both of said energizing circuits, a first relay associated with, and controlled by, each of the signal control means, a stick relay associated with each of the signal control means and controlling the energizing circuit of the other signal control means, each of said stick relays having a pick-up circuit controlled by said traffic responsive means, and a stick circuit for each stick relay controlled by its respective signal control means.

6. In a traffic control system for single track, signal control means for governing traffic in one direction, signal control means for governing traffic in the opposite direction, an energizing circuit for each of the signal control means, a traffic responsive means controlling both of said energizing circuits, a slow acting first relay associated with, and controlled by, each of the signal control means, a stick relay associated with each of the signal control means and controlling the energizing circuit of the other signal control means, each of said stick relays having a pick-up circuit controlled by said traffic responsive means.

7. In a single track traffic control system, signal control means for traffic in one direction, signal control means for traffic in the opposite direction, a traffic responsive means controlling the energizing circuits for said signal control means, a stick relay associated with each of the signal control means and controlling the energizing circuit for the other signal control means, a pick up circuit for each of the stick relays, a relay associated with, and controlled by, each signal control means, said pick up circuit for each stick relay including a contact of its associated said relay, a contact of the traffic responsive means, a contact of the other said relay, and a contact of the other stick relay.

8. In a single track traffic control system,

signal control means for traffic in one direction, signal control means for traffic in the opposite direction, a traffic responsive means controlling the energizing circuits for said signal control means, a stick relay associated with each of the signal control means and controlling the energizing circuit for the other signal control means, a pick up circuit for each of the stick relays, a relay associated with, and controlled by, each signal control means, said pick up circuit for each stick relay including a front contact of the associated said relay, and a back contact of the other said relay.

9. In a single track traffic control system, signal control means for traffic in one direction, signal control means for traffic in the opposite direction, a traffic responsive means controlling the energizing circuits for said signal control means, a stick relay associated with each of the signal control means for controlling an energizing circuit for the other signal control means, a pick up circuit for each of the stick relays completed through a back contact of the other stick relay, whereby to prevent completion of the pick up circuits of both stick relays at any one time.

10. In a single track traffic control system, signal control means for traffic in one direction, signal control means for traffic in the opposite direction, a traffic responsive means controlling the energizing circuits for said signal control means, a stick relay associated with each of the signal control means and controlling the energizing circuit for the other signal control means, a pick up circuit for each of the stick relays, the stick relays being cross connected to prevent simultaneous pick up of the same.

11. In a single track railway system, a signal governing traffic in one direction, another signal governing traffic in the other direction, a stick relay associated with each of said signals which when energized permits the next signal in the rear to assume the caution position, and pick-up circuits for said stick relays interlocked with said stick relays so that only one of said stick relays can be picked up at one time.

12. In a single track railway system, a signal governing traffic in one direction, another signal governing traffic in the other direction, a stick relay associated with each of said signals which when energized permits the next signal in the rear to assume the caution position, a pick-up circuit for one stick relay including a back contact of the other stick relay, and a pick-up circuit for said other stick relay including a back contact of said one stick relay.

13. In a single track railway system, a signal governing traffic in one direction, another signal governing traffic in the other direction, a stick relay associated with each of said signals which when energized permits the next

signal in the rear to assume the caution position, a pick-up circuit for one stick relay including a line wire and a contact closed when the other stick relay is de-energized, and a 5 pick-up circuit for the other stick relay including the same line wire and a contact closed when said one stick relay is de-energized.

In testimony whereof I affix my signature.
